UNITED STATES PATENT OFFICE.

ASHLAND C. HITCHCOCK, OF TESCOTT, KANSAS.

NEST.

1,396,432.

Specification of Letters Patent.

Patented Nov. 8, 1921.

Application filed March 30, 1921. Serial No. 456,923.

To all whom it may concern:

Be it known that I, ASHLAND C. HITCHCOCK, a citizen of the United States, residing at Tescott, in the county of Ottawa and 5 State of Kansas, have invented certain new and useful Improvements in Nests, of which the following is a specification.

This invention relates to nests for hens and one object of the invention is to provide 10 a nest which will prevent the hen occupying it from being disturbed while she is in the nest. A further object of the invention is to provide means whereby the entrance of a hen into the nest will be invited, and exit 15 therefrom will be facilitated but her exit through the entrance will be prevented. Other incidental objects of the invention will appear in the course of the following description.

20 In the accompanying drawings—

Figure 1 is an elevation of my improved nest in its operative position;

Fig. 2 is an enlarged longitudinal section;

Fig. 3 is a plan view.

25 In carrying out my invention, I provide a shelf or platform 1 which may be conveniently and, preferably, is set within an opening 2 in a fence or partition 3 which partition may be within a hen house. Upon 30 the shelf 1, I provide the spaced posts or brackets 4 and between the said posts I pivotally mount a box 5. This box may be of any inexpensive material, and sheet metal may be advantageously employed. The box 35 is preferably rectangular with its longitudinal dimension in the line of the fence or partition 3 and its transverse dimension disposed at an angle to the partition. The 40 pivots by which the box is mounted upon the posts 4 are secured in the sides of the box at the center of the same and at the opposite sides thereof. Both ends of the box are closed, as shown at 6, but in each side is a door opening 7, the said openings, 45 however, being disposed at opposite ends of the box. A door 8 is arranged to cover each opening and each door is hingedly mounted upon the box at the adjacent end of the same so that the free edge of the 50 door will be disposed toward the center of the box. The doors are mounted so as to move freely, and extending across the top of the box is a coupling bar or link 9 which has its opposite ends loosely pivoted to the 55 upper corners of the free ends of the respectively adjacent doors.

Within the box and between the pivotal point thereof and the entrance end thereof, is a transverse cleat or rail 10, the space between the said rail and the nearer end 60 of the box being filled or partly filled with sand or some similar material, as indicated at 11, so that the said end of the box will be overweighted and the box will normally assume the position shown in full lines in 65 Fig. 2. Between the cleat or rail 10 and the more remote end of the box, the nest, indicated at 12, is made and a nest egg 13 is placed therein.

Normally, the box will assume the position shown in Fig. 1 and in full lines in Fig. 2, with the entrance end thereof lowered. Inasmuch as the doors 8 are each hinged at the end of the box, the tilted position of the box will cause the door 8, at 75 the entrance end, to swing open while the door at the exit end will be drawn to closed position against the side of the box, as shown clearly in Fig. 3. The coupling bar or link 9 forces the doors to move simultaneously 80 so that the entrance and the exit openings cannot both be fully uncovered at one time. When a hen enters the box, she will at once step over the rail 10 and occupy the nest 12, her weight then overcoming the weight 11 85 so that the box will assume the position shown in dotted lines in Fig. 2, this tilting of the box causing the exit door to swing to open position while the entrance door will close. When the hen leaves the nest 90 through the exit door opening the nest will return to the initial position inasmuch as it is then relieved of the weight of the hen and the weight 11 is free to act. The device is exceedingly simple and inexpensive and 95 is efficient in its operation. By its use, the laying hens are free from annoyance and inasmuch as they cannot enter and leave at the same side the working hens will soon be all together at one side of the partition, 100 while the drones will be at the opposite side, and the owner of the brood will be thereby enabled to intelligently select the fowls desirable for laying and others for fattening for the market. This separation of the 105 brood will obviously be accomplished without any attention upon the part of the owner.

Having thus described the invention, what is claimed as new is:

1. A nest comprising a receptacle mounted for tilting movement and provided in its

- opposite sides at its opposite ends with outwardly swinging doors.
2. A nest comprising a receptacle mounted between its ends for tilting movement and provided in its opposite sides at its opposite ends with door openings, doors hinged at the ends of the receptacle to cover the respective openings, and a coupling between the free edges of the doors.
- 10 3. A nest comprising a receptacle having closed ends and having a door opening in each side at one end thereof, means within the receptacle to hold the same normally in one position, doors hinged upon the opposite sides of the receptacle at the opposite ends

thereof to close the respectively adjacent door openings, and a coupling bar extending across the receptacle and having its opposite ends loosely pivoted to the free ends of the respective doors.

20

4. A nest comprising a receptacle mounted for tilting movement, laterally swinging doors at the opposite sides of the receptacle arranged to swing to open position as the respective side of the receptacle lowers, and a coupling connecting the free edges of the doors whereby one door will close as the other door opens.

25

In testimony whereof I affix my signature.

ASHLAND C. HITCHCOCK. [L. s.]
